ATTORNEY.

UNITED STATES PATENT OFFICE

ROY HERBERT CUNNINGHAM, OF JACKSON, MICHIGAN, ASSIGNOR TO THE REYNOLDS SPRING COMPANY, OF JACKSON, MICHIGAN

ATTACHMENT PLUG FOR ELECTRIC HEATING DEVICES

Application filed July 15, 1927. Serial No. 205,951.

This invention relates to an attachment plug for electric heating devices and has for its object to provide a simple, inexpensive, durable and effective device of this nature.

With the above and other objects in view, the invention consists in the construction and novel combination and arrangement of parts hereinafter described, illustrated in the accompanying drawings and set forth in the claims hereto appended, it being understood that various changes in the form, size and minor details of construction may be resorted to, within the scope of the claims, without departing from the spirit of the invention or sacrificing any of the advantages thereof.

In the drawings:

Fig. 1 is an elevation of one section of the insulating body, the operative parts being removed.

Fig. 2 is a longitudinal sectional view through one of the contacts and the insulating body.

Fig. 3 is a central longitudinal view through the insulating body.

Fig. 4 is an enlarged detail elevation of one of the contacts removed from the insulating body.

Fig. 5 is a similar view taken from another side of the contact.

Fig. 6 is a transverse sectional view of the contact.

Fig. 7 is an end view.

Referring now more particularly to the accompanying drawings, the reference character A indicates a body of insulating material comprising two sections 8 and 9 of molded insulating material and each provided with a marginal rib 10 and having centrally arranged forked ribs B, including the central longitudinal portions 11 and the diverging fork-arms 12, these ribs being fitted together to form a brace and division members.

The central longitudinal portions 11 are arranged in spaced relation with the marginal ribs 10 to provide side recesses 13 having smooth walls for the reception of the contacts C. The upper portions of the sections are laterally enlarged to form similar slightly projecting segments 14 serrated exteriorly to

provide grips for the ready removal of the heater plug from an electric heating device. The arms 12 of the ribs B have their outer or free ends terminating short of the marginal ribs to provide passages 15 between the outer ends of said fork arms 12 and the marginal ribs 10 for the end portions of the wires of an electric cord 16 for connecting the heater plug with an electric fixture or other suitable source of current supply.

The insulating body A is provided with a circular opening 17 through which the electric cord passes, and this cord is passed through a coil spring 18 having an enlarged portion 19 fitting within an annular groove 20 in the wall of the circular opening 17. When the sections of the body A are assembled and clamped together by the fastenings 21, the enlarged portion 19 of the coil spring is securely held in the said annular groove 20 of the plug.

The coiled spring 18 carries a bushing 22 at its outer end and this bushing is formed of insulating material. The wires of the electric cord are spread at the top of the forked rib A and the ends extended around the outer ends of the fork arms 12 and are secured by binding screws 23 of the contacts C of the plug.

The contacts C of the heater plug are adapted to fit snugly within the recesses 13 and each is composed of a single strip of copper, bronze or other suitable conducting material bent at its center to form overlapping portions constituting a shank 24. These portions of the shank are bent outwardly in opposite directions at the inner end of the shank to provide offset side portions 25 from which are extended the sides 27, which latter at their extremities are flared in rounded formation, as at 28, away from each other, and thence bent back upon their flaring portions and from the flaring portions directed rearwardly in parallelism and overlapping or in contact with each other between the converging sides 29 to form contact tongues 29. The rounded formation or flaring of the extremities of the converging side portions overcomes cutting of the plug body incident to sharp edges.

Each converging side portion 27 of each

contact C has a spring finger 30 struck up therefrom leaving a longitudinal slot 31 therein. These fingers are yieldable and stand out from the opposite converging sides of the contact and as these fingers press against the walls of the recesses 13 of the plug they give a double spring effect without causing the contact to grip the heater plug when inserted therein or withdrawn to the extent of causing undue resistance in the passage of the plug into or out of the contact. The spring fingers 30 render the contacts self-centering, the fingers exerting equal pressure on the walls of casing sections 8 and 9 and thereby centering the contacts with relation to the openings at the end of the recesses, which insures the reception of the plugs of the iron, toaster, or other device between the tongues 29. This overcomes the possibility of flat or other plugs, especially flat plugs, entering the attachment between one of the sides 27 of the contact and the wall of the plug A, which would be an improper and inefficient or partial contact. Thus the present contact is provided with spring fingers 30 to perform the dual function of overcoming undue wear on the insulating casing and to center the same for the effecting reception of the iron, toaster, or other plug, irrespective of shape of the latter. This form of contact insures against formation of sharp edges which are liable to cut into the plug body of insulating material when inserting and removing the plug of the connected device. The present contact is yieldable and cutting of the body of the plug is overcome and the fingers 30 maintain the present contacts in centered position, as stated.

The aforesaid longitudinal slots 31 from which said spring fingers 30 are struck are preferably partially closed, that is, they are closed at their outer ends by the formation of grooves 32 pressed or otherwise formed in and throughout the length of the aforesaid tongues 29. By virtue of the formation of these grooves 32 in the tongues 29 the said slots are intersected by said grooves and partially closed, as stated, and a full bearing of the metal upon the device inserted in the contact is obtained. As shown, the grooves 32 of the tongues 29 extend through the flaring portions 28 to present a substantially round or circular mouth at the outer end of the contact, which, together with the flared outer end of the contact, greatly facilitates insertion of a device into and between the tongues 29 of the contact.

For the purpose of providing a substantial base of metal to hold the terminal screw 33, a plate 34 is secured to the shank 24 by means of bent fingers 35. The plate 34 is provided on its outer face with lugs 36 opposite the threaded opening through which the terminal screw 33 operates.

What is claimed is:

1. A contact member comprising a single piece of metal bent upon itself to form portions which are arranged in contact at the bend to form a shank, said shank portions at their free ends directed outwardly in opposite directions and thence directed toward each other to form converging side portions having their ends flared in rounded formation away from each other, and thence bent back rearwardly upon the flared portions and extending between the converging side portions to form tongues lying one upon the other, and yieldable fingers struck up from end extending outwardly from said converging side portions and resulting in the formation of slots in said converging side portions, said tongues having oppositely disposed longitudinal grooves whereby to substantially embrace an inserted plug, the grooves of said tongues intersecting the said slots and partially closing the latter and extending into said flared portions. 75 80 85

2. A contact member comprising a single piece of metal bent upon itself to form a shank and at the free end of the shank being directed outwardly in opposite directions and thence bent to provide side portions having their ends flared outwardly in rounded formation and thence bent backwardly and extending rearwardly between said side portions to form yieldable tongues arranged between said side portions, and yieldable fingers struck up from the side portions, said tongues having oppositely disposed longitudinal grooves extending throughout their lengths and leading to the flared ends of the side portions. 90 95 100

3. A contact member comprising a single piece of metal bent upon itself to form a shank and at the free end of the shank offset laterally in opposite directions and thence bent to form converging side portions and thence directed rearwardly between said side portions to provide yieldable tongues, the tongues having oppositely disposed longitudinally extending grooves to receive a plug inserted between the tongues and of a length to embrace the plug substantially through its length, and yieldable fingers struck up from the side portions and extending outwardly therefrom. 105 110 115

4. A contact member comprising a single piece of metal bent upon itself to form a shank and at the free end of the shank offset laterally in opposite directions and thence bent to form converging side portions and thence directed rearwardly between said side portions to provide yieldable tongues, the tongues having oppositely disposed longitudinally extending grooves to receive a plug inserted between the tongues and of a length to embrace the plug substantially throughout its length, and yieldable fingers struck up from the side portions and extending outwardly therefrom and resulting in 120 125 130

slots in the side portions, said grooves in said tongues intersecting said slots.

5. A contact member comprising a single piece of metal bent upon itself to form a shank and at the free end of the shank being directed outwardly in opposite directions and thence to provide side portion provided with openings and having their ends flared and thence bent backwardly and extending rearwardly between the side portions to form yieldable tongues arranged between said side portions, the said tongues intersecting the openings in the side portions.

10 In testimony whereof I have hereunto set
15 my hand.

ROY H. CUNNINGHAM.
